UNITED STATES PATENT OFFICE.

SIMON S. CREIDER AND ISAAC KORN, OF STERLING, ILLINOIS.

CORN-HUSKING AND FODDER-SHREDDING MACHINE.

SPECIFICATION forming part of Letters Patent No. 738,776, dated September 15, 1903.

Application filed May 8, 1902. Serial No. 106,476. (No model.)

To all whom it may concern:

Be it known that we, SIMON S. CREIDER and ISAAC KORN, citizens of the United States, residing at Sterling, in the county of White-
5 side and State of Illinois, have invented a new and useful Corn-Husking and Fodder-Shredding Machine, of which the following is a specification.

Our invention is an improved corn-husking and fodder-shredding machine; and it consists in the peculiar construction and combination of devices hereinafter fully set forth and claimed.

In the accompanying drawings, Figure 1 is a vertical longitudinal sectional view of a corn-husking and fodder-shredding machine embodying our improvements. Fig. 2 is a top plan view of the same, partly in section, on a plane indicated by the line *a a* of Fig. 1. 15 Fig. 3 is a detail transverse sectional view taken on a plane indicated by the line *b b* of Fig. 2. Fig. 4 is a detail perspective view of a pair of the shredding-disks. Fig. 5 is a similar view showing a modified form of the shredding-disk. Fig. 6 is a diagrammatic top plan view showing several arrangements of the shredding-rollers with reference to the snapping-rolls.

In the embodiment of our invention we employ a pair of snapping-rolls 1, each of which comprises a plurality of circular disks 2, spaced apart by collar-disks 3, which are of less diameter than the disks 2. The latter are provided with peripheral teeth 4, which 20 extend transversely thereof and are triangular in cross-section. The collar-disks have similar peripheral teeth 5, which are smaller than the teeth 4 of the disks 2, and owing to the difference in size between the disks and the collar-disks the teeth of the latter are disposed within the radius of the teeth on the disks 2. The larger disks 2 of the respective snapping-rolls are intercurrent—that is to say, the disks 2 of each snapping-roll are disposed opposite the smaller collar-disks of the opposing roll—and the peripheries of the said disks 2 of the respective snapping-rolls overlap each other, but not to such an extent as to cause the teeth 4 of the disks 2 to engage or be 25 disposed within the radius of the teeth of the collar-disks. Hence spaces are formed between the respective peripheries of the disks

and collar-disks which admit of the passage of cornstalks moving endwise with respect to their own lengths and transversely with 55 respect to the snapping-rolls, so that the cornstalks as they pass between the snapping-rolls will be disintegrated and broken, as will be understood. In addition to their function in disintegrating and breaking the cornstalks 60 the snapping-rolls act efficiently as such to snap the ears of corn from the stalks as the latter pass between the snapping-rolls.

The snapping-rolls are here shown as mounted transversely in a frame 6. The latter may be either of the form here shown or of any other suitable construction, and within the scope of our invention the snapping-rolls may be rotated by any suitable means. They are here shown as provided at one end of 70 their respective shafts with intermeshed spur-gears 7, which cause the said snapping-rolls to rotate in opposite directions. A pulley 8 is shown on the shaft of one of the snapping-rolls, and the said pulley is connected by an 75 endless belt 9 to a pulley 10 on one end of a shaft 11, which shaft is journaled in bearings at the feed end of the frame and is provided with a plurality of eccentrics 12. The latter project in different directions from the shaft 80 11. As here shown, alternately-disposed eccentrics project in opposite directions from the shaft; but we do not limit ourselves in this particular. The eccentric-straps 13 on the eccentrics 12 are connected by pitmen 14 to 85 longitudinally-movable feed-bars 15. The latter are here shown as having their outer ends disposed to move in guides 16 and are supported near their inner ends by oscillating links 17, which are shown as pivotally connected thereto and to a transversely-disposed supporting-bar 18. The upper sides of the feed-bars are provided with feed-teeth 19. The feed-bars 15 are substantially of the same construction as the feed-bars shown and described in the patent granted to Isaac Korn and S. S. Creider September 13, 1898, No. 610,713, and the same serve to feed bundles of corn endwise to the snapping-rolls, as will be understood. The feed-bars form the bottom of a feed-trough the sides of which are formed by the casing at the sides of the frame 6, as shown at 20 in Figs. 1 and 2. 95 100

The inner ends of the reciprocating feed-

bars 15 are at some distance from the snapping-rolls, and in order to prevent the space between the inner ends of the feed-bars and the snapping-rolls from becoming choked we 5 provide throat-feed plates 21, which are preferably of the construction shown in Figs. 1 and 2, and are sufficiently wide to almost completely bridge the space between the sides of the frame and immediately in front of the 10 snapping-rolls. The feed-bars, which are considerably narrower, are spaced apart, as shown in Fig. 2. The throat feed-plates, by being secured to the inner ends of the feed-bars, are moved back and forth by the latter and serve 15 to prevent an accumulation of material in advance of the snapping-rolls, and are particularly useful in feeding the latter with loose or tangled material. It will be understood that as the stalks of corn pass between the 20 snapping-rolls the ears are snapped therefrom by the action of the snapping-rolls and fall directly therefrom onto the longitudinally-inclined husking-rolls 22, which are shown in Fig. 1. These husking-rolls are 25 preferably of the construction shown and described in Letters Patent of the United States No. 613,249, granted to us November 1, 1898, and need not, therefore, be more fully described in this specification.

30 At the rear ends of the husking-rolls and in line therewith are shredding-rolls 23. The same are formed of a plurality of intercurrent-disks spaced apart by collar-disks and of the same construction and relative arrangement as the disks or collar-disks which form the snapping-rolls, hereinbefore described. It will be observed by reference to Figs. 1 and 2 that the shredding-rolls 23 are disposed at right angles to the snapping-rolls 1 and 40 with their lower ends below the snapping-rolls. Hence the cornstalks which pass between the snapping-rolls are delivered onto the shredder-rolls and substantially parallel with the latter in such position that the fodder is caught by the teeth of the disks of the shredder-rolls and drawn downwardly between the same and subjected to the shearing action of the overlapping toothed edges of the disks of the shredding-rolls, and thereby 45 cut into lengths equal to the width or thickness of the said disks. Owing to the fact that the fodder passes between the snapping-rolls at substantially right angles to their axes, the fodder, although crushed, broken, and disintegrated by the snapping-rolls, is not cut into short lengths thereby, but is delivered therefrom onto the shredding and cutting rolls 23. The bands of twine, however, with which the bundles of fodder are 55 tied are caught by the overlapping intercurrent toothed edges of the disks of the snapping-rolls and cut by the shearing action thereof, thereby causing the fodder to be loosely fed to the shredding-rolls.

60 To prevent the fodder as it is delivered from the snapping-rolls from accumulating in masses on the shredding and cutting rolls

and to regulate the feed thereof to the shredding and cutting rolls, we provide a regulating-gate 24, which is hung above the shredding and cutting rolls and transversely in the frame 1, under a cover 25, which extends from above the snapping-rolls to the rear end of the frame, and the said regulating-gate is hinged at its upper side, as at 26. The same 70 normally is disposed by gravity in the position shown in Fig. 1. As the fodder passes under the gate 24 the latter swings rearwardly on its hinge; but owing to its weight the regulating-gate prevents the corn-fodder from being fed in masses from the snapping-rolls to the shredding-rolls. 75

Any suitable number of the shredding-rolls may be used. We here show two pairs of them in Fig. 2. Within the scope of our invention any appropriate means may be employed for driving the shredding and cutting rolls. For the purposes of this specification the rolls of the respective pairs are shown connected together by intergeared spur-wheels 27, and the shaft of one of each pair of shredding and cutting rolls is shown connected to a power-shaft 28 by miter-gears 29. We also show this power-shaft connected to the shaft of one of the snapping-rolls by pulleys 30 31 and an endless belt 32. 80

Pairs of shredding and cutting rolls are shown as separated by a crest or divider-bar 33. We also provide a throat-guide 34, which is preferably of the form shown in Figs. 1, 2, and 3, covers the snapping-rolls, extends rearwardly therefrom over the lower portions of the inclined cutting and shredding rolls, and has its sides contracted rearwardly, so that its discharge end is of the width of the combined set of cutting and shredding rolls, and it will be understood that the said throat-guide serves to feed the fodder from the snapping-rolls to the cutting and shredding rolls. 90

It will be observed by reference to Fig. 1 of the drawings that the shredding and cutting rolls are inclined and extend upwardly beyond the snapping-rolls. This causes the fodder to be so disposed longitudinally of the shredding and cutting rolls as to facilitate the action of the shredding and cutting disks in grasping the fodder and drawing it between the pairs of shredding and cutting rolls, so that each stalk becomes cut in a number of short pieces. The lightest fodder drops from the snapping-rolls directly onto the rear lower portions of the shredding and cutting rolls, and is therefore cut into but few lengths. The heavier the fodder and the stiffer the stalks thereof the farther it is fed upwardly on the inclined shredding and cutting rolls by the snapping-rolls and the throat-feed, and hence the same is caused to be cut into a number of short pieces and its value as feed considerably enhanced. The husks are delivered 100 from between the husking-rolls 22 and fall therefrom. The ears slide downwardly on the husking-rolls and fall from the lower ends thereof. The cut and shredded fodder drops 105

from between the cutting and shredding rolls, as will be understood. An inclined discharge-trough 35 is shown in Fig. 1 of the drawings to catch the cut and shredded fodder and discharge the same by gravity from the machine.

In Fig. 5 of the drawings we show a modification in the construction of the disks of our snapping and shredding rolls in which the disks are provided midway between their sides and between the bases of their teeth 4 with smaller teeth 4^a, which are triangular in cross-section and which increase the efficiency of the disks in grasping the fodder and drawing the same between the rolls.

15 While we have shown the snapping-rolls in Figs. 1 and 2 of the drawings as disposed with their axes at right angles to the axes of the shredding and cutting rolls, we do not desire to limit ourselves in this particular, as the 20 cutting and shredding rolls may be disposed at other than right angles with reference to the snapping-rolls. In the diagram Fig. 6 the cutting and shredding rolls are shown disposed in three positions with reference to the 25 snapping-rolls. Other variations may be made in the relative dispositions of the shredding and snapping rolls within the scope of our invention and the appended claims.

We desire to lay especial stress upon the 30 function of the snapping-rolls in cutting the binding-twine, as well as snapping the ears from the stalks and crushing and disintegrating the fodder prior to feeding the same to the shredding-rolls. By thus adapting the 35 snapping-rolls to cut the bands of twine by which the corn is bound the fodder is fed in a loose condition from the snapping-rolls to the shredding-rolls and is adapted to readily pass between the shredding-rolls and to be cut 40 into short lengths thereby. The binding-twine after having been cut by the snapping-rolls drops upon the shredding-rolls, together with the fodder, and is also cut into short lengths. In practice the snapping-rolls of our 45 improved machine rotate at a comparatively low rate of speed, and the twine is carried between them, together with the fodder. Should the twine become caught and partly wrapped upon the snapping-rolls, the free end thereof 50 would be caught by the shredding-rolls, and hence twine will be drawn from the snapping-rolls by the shredding-rolls. The continuous rotation of the snapping-rolls and shredding-rolls and the peculiar construction thereof 55 insures the cutting of the twine-bands into short lengths and the feeding of the fodder evenly from the snapping-rolls to the shredding-rolls.

Having thus described our invention, we 60 claim—

1. Coacting paired rolls having disks overlapping and contacting to form shear edges, in combination with coacting paired rolls having disks with overlapping contacting shear

edges, the last-named rolls being disposed at 65 an angle to and coöperating with the first-named rolls.

2. Coacting paired cutting-rolls having intercurrent, overlapping, peripherally-toothed disks and peripherally-toothed collar-disks 70 intermediate the first-mentioned disks, the peripheries of the opposite disks and the collar-disks being spaced apart, and the overlapping disks coacting to form shears.

3. In combination with snapping-rolls, cutting and shredding rolls disposed at an angle with reference thereto with their lower ends extended under said snapping-rolls and their upper ends inclined and extended upwardly and outwardly therefrom, substantially as described. 75

4. In combination with snapping-rolls, reversely longitudinally movable feed-bars, having throat-feed plates at their inner ends disposed opposite the snapping-rolls, substantially as described. 80

5. In combination with peripherally-toothed snapping-rolls, means to feed corn longitudinally with respect to its stalks to said snapping-rolls, at an angle to the axes of the latter, whereby the cornstalks are drawn between and crushed and disintegrated thereby, and cutting-rolls having overlapping disks, and disposed at such an angle with reference to the snapping-rolls, that the stalks delivered 95 from the latter are fed longitudinally on the cutting-rolls and substantially parallel with the axes thereof, substantially as described. 9c

6. In combination with snapping-rolls, cutting-rolls disposed at an angle thereto and fed thereby, and a regulating-gate suspended above the cutting-rolls, substantially as described. 100

7. In combination with snapping-rolls, cutting-rolls disposed at an angle thereto and fed thereby, and a regulating-gate, hingedly supported at its upper side and disposed above the cutting-rolls and in rear of the snapping-rolls, substantially as described. 105

8. In combination with snapping-rolls, cutting-rolls disposed at an angle thereto, below the same and fed thereby, and a throat-feed over and extending rearwardly from the snapping-rolls and having rearwardly-converging sides, substantially as described. 110 115

9. A disk for a corn snapping or shredding roll having a serrated periphery, and formed with minor serrations alternating with major serrations.

In testimony that we claim the foregoing as 120 our own we have hereto affixed our signatures in the presence of two witnesses.

SIMON S. CREIDER.
ISAAC KORN.
